UNITED STATES PATENT OFFICE

2,613,475

STRIKING TOY

Adrien R. Mellor, Loma Linda, Calif.

Application February 4, 1949, Serial No. 74,581

4 Claims. (Cl. 46—1)

1

This invention relates to a novel construction of striking or hammering toy for use by children embodying a body member which is adapted to be manually held and by means of which a striking or hammering force is exerted in combination with an element which is reciprocally mounted in and carried by the body member and an end of which is adapted to be struck against a solid surface by the impact stroke of the body member to cause said element to slide relatively to the body member and to thereby simulate the use of a hammer, mallet or similar tool.

Another object of the invention is to provide a toy having means connected to a portion or portions thereof which are adapted to strike a stationary surface to prevent injury or damage to furniture or a floor surface when the toy is used indoors.

Another object of the invention is to provide a toy which is relatively small and compact and containing no normally detachable parts which may become lost or misplaced.

Another object of the invention is to provide a toy of extremely simple and compact construction capable of being economically manufactured and sold and which will be extremely efficient and durable for its intended purpose and of educational value to children.

Numerous other objects and advantages of the invention will hereinafter become more fully apparent from the following description of the drawings, illustrating the presently preferred embodiments thereof, and wherein:

Figure 1 is a side elevational view, partly in section showing a preferred form of the toy;

Figure 2 is a sectional view thereof taken substantially along a plane as indicated by the line 2—2 of Figure 1;

Figure 3 is a fragmentary side elevational view of a slightly different embodiment of the invention;

Figure 4 is a sectional view thereof taken substantially along a plane as indicated by the line 4—4 of Figure 3;

Figure 5 is a side elevational view, partly in section of another form of the invention;

Figure 6 is a cross sectional view thereof taken substantially along a plane as indicated by the line 6—6 of Figure 5;

Figure 7 is a side elevational view, partly in section of a modification of the form of Figures 1 and 2;

Figure 8 is a sectional view thereof taken substantially along a plane as indicated by the line 8—8 of Figure 7;

Figure 9 is a sectional view taken substantially along a plane as indicated by the line 9—9 of Figure 7 and with a portion of the structure shown in side elevation;

Figure 10 is a fragmentary side elevational view, partly in vertical section of a variation of the form of the invention as illustrated in Figures 3 and 4;

Figure 11 is a sectional view thereof taken substantially along a plane as indicated by the line 11—11 of Figure 10;

Figure 12 is a fragmentary side elevational view of another form of the invention, and

Figure 13 is a sectional view thereof taken substantially along a plane as indicated by the line 13—13 of Figure 12.

Referring more specifically to the drawings, and first with reference to the form of the invention as illustrated in Figures 1 and 2, the hammering or striking toy disclosed therein is designated generally 15 and includes a body member, designated generally 16 constituting a hammer or mallet and composed of a head 17 and a handle 18. The head 17 is relatively long and has a bore 19 extending longitudinally therethrough and is also provided, intermediate of its ends, with a transversely extending recess 20 one end of which opens outwardly of a portion of the head 17 and the other of which extends to nearly the opposite side of said head so that the recess 20 intersects the bore 19. The handle 18 is provided with a shank end 21 which is shaped to snugly fit into the recess 20 and which is provided with a transverse bore 22 which is adapted to register with the ends of the bore 19 when said shank 21 is fully inserted into the recess 20.

The hammering or striking toy 15 also includes an elongated peg or rod 23 which is sized to extend reciprocally through the bores 19 and 22 and which forms a relatively snug fitting engagement therewith. As the description proceeds it will be readily apparent that a bar, tube or pipe may be utilized in lieu of the peg or rod 23 and instead of being circular in cross section, as illustrated, may be of any desired cross sectional shape corresponding or substantially corresponding to the cross sectional shape and size of the bores 19 and 22. The peg or rod 23 may be formed of various materials which are relatively resilient and is provided with corresponding slots 24 which extend diametrically thereacross and from the ends of the peg or rod 23 inwardly thereof to beyond the intermediate portion of the peg or rod so that the inner ends of

the slots 24 overlap. It will also be apparent that the slots 24 are disposed at right angles to each other, as clearly illustrated in Figures 1 and 2. The surfaces of the peg or rod 23 may be inscribed with suitable indicia longitudinally thereof such as the numerals 25 or lettering or other indicia, not shown, may be employed for indicating the distance that the peg or rod is driven relatively to the head 17, as will herein-after become apparent. A protective cap or tip 26 is applied to each end of the peg 23, said caps 26 preferably being formed of rubber and including a recess or socket 27 for receiving an end of the peg 23. The caps 26 may be frictionally retained on the ends of the peg 23 or may be suitably bonded thereto.

From the foregoing it will be readily apparent that the toy 15 may be utilized by a child by grasping the handle 18 similarly to a hammer or mallet and by striking with the body member 16 so that the cap 26 at one end of the peg or rod 23 will be struck with an impact force against a solid surface. The inertia force of the striking blow will cause the hammer or mallet 16 to slide relatively to the peg 23 upon impact of one end of the peg with a solid surface and the movement of said hammer or mallet 16 will be toward the end of the peg which strikes the surface. The indicia 25 will indicate the distance of travel of the hammer head 17 relatively to the peg 23. The slots 24 will permit the end portions of the peg 23 to expand and will likewise permit the end portion, toward which the hammer head moves, to yield inwardly or contract so that a frictional gripping engagement will exist between the peg and the bores 19 and 22. As the hammer head 17 approaches one end of the peg 23, the head is inverted so that the other capped end of the peg becomes the impact receiving end of the toy 15 as the hammer or mallet head 17 is driven along the peg in the opposite direction. It will also be apparent that centrifugal force created by swinging the hammer or mallet in the impact stroke will tend to cause the head 17 to pull away from the handle 18 to create an additional binding action of the bore 22 with the peg 23 which will additionally function to resist sliding movement of the peg through the hammer or mallet head and handle. It will be apparent that the caps or tips 26 will protect any surface against which the peg 23 is struck.

Figures 3 and 4 illustrate another form of the invention, designated generally 28 and wherein, in lieu of the hammer or mallet 13, the toy 28 is provided with a body, designated generally 29 including an elongated handle 30 having a disk-shaped head 31 formed integral with one end thereof and which is provided with an opening 32 extending therethrough from side-to-side thereof. The opening 32 is sized to slidably receive a peg or rod 33 which extends reciprocally therethrough and which is identical in construction with the rod 23 and has caps or tips 34 at each end thereof. The head or disk 31 may be made of any desired size or thickness in a direction longitudinally of the rod 33.

The handle 30 may be of any desired length and is grasped in the same manner as the handle 18 for utilizing the toy 28 in the same manner and for the same purpose as previously described with respect to the toy 15.

Figures 5 and 6 illustrate another and different embodiment of the invention which likewise embodies a striking toy, designated generally 35 including a peg or rod 36 corresponding to the

peg or rod 23 and likewise provided with caps or tips 37. In lieu of a mallet or hammer-type body, the toy 35 is provided with an elongated body 38 shaped generally like a dumbbell and including enlarged, substantially spherical-shaped end portions 39 and a restricted intermediate portion 40, formed integral with said end portions and providing a handle adapted to be manually grasped. The body 38 is provided with a bore 41 extending longitudinally therethrough from end-to-end of the portions 39 and 40 in which the peg 36 is reciprocally disposed and yieldably gripped. By grasping the handle portion 40 either capped end 37 of the peg 36 can be struck against a surface to cause the body 38 to slide on said peg and toward said end, and by inverting the toy 35, it may be similarly employed for driving the body 38 toward the opposite end of the peg.

Figures 7 and 8 illustrate another embodiment of the striking or hammering toy, designated generally 42 and which constitutes a variation of the form as illustrated in Figures 1 and 2 and which includes a body, designated generally 43, constituting a hammer or mallet and comprising a head 44 and handle 45. The head 44 has a bore 46 extending longitudinally therethrough and is provided with a transverse recess 47 intermediate of its ends which opens outwardly of one side thereof and which extends inwardly to beyond the center of the head 44 to intersect the bore 46. The handle 45 is provided with a shank end 48 which is shaped and sized to snugly engage the recess 47 and which is provided with a bore 49 which is larger than the bore 46 and which is lined with a sleeve 50 of a resilient material such as rubber. The bore of the sleeve 50 registers with the end portions of the bore 46 when the shank 48 is fully inserted in the recess 47. The toy 42 also includes an elongated peg or rod 51 which differs from the peg 23 in that it is not provided with longitudinally extending slots. Likewise, it will be readily apparent that the peg 51 could be of tubular formation. The peg 51 extends reciprocally through the bore 46 and through the bore of the sleeve 50 which latter bore is of a slightly smaller diameter than the bore 46 to yieldably grip the peg 51 to frictionally resist its sliding movement relatively to the head 44. A cap or tip 52, corresponding to the caps 26 is applied to each end of the peg 51.

The toy 42 is utilized in the same manner as the toy 15 and it will be readily apparent that the sliding movement of the head 44 relatively to the peg 51 will be resisted by frictional engagement of the sleeve 50 with said peg and centrifugal force will tend to displace the handle 45 relatively to the head 44 to move the sleeve 50 out of registry with the bore 46 to increase this frictional resistance.

Figures 10 and 11 illustrate another embodiment of the toy, designated generally 53 and which constitutes a variation of the form thereof as illustrated in Figures 3 and 4 and which includes a body member, designated generally 54 composed of a handle 55 and an integral disk-shaped head 56, corresponding to the body member 29 except that the bore 57 of the head 53 is enlarged relatively to the diameter of the peg or rod 58, which corresponds to the peg 51, and is equipped at its ends with caps 59. The bore 57 is lined with a grommet or sleeve 60 of a yieldable material having enlarged or flanged ends 61 which seat against the opposite sides of

the head 56 and the bore of which sleeve 60 is normally slightly smaller than the peg 58 so that the sleeve 60 will be compressed when the peg extends therethrough to frictionally resist sliding movement of the peg relatively to the head 56. The toy 54 is utilized in the same manner and for the same purpose as the toys 15, 28 and 42.

Figures 12 and 13 illustrate still another embodiment of the invention, designated generally 62 including a body member, designated generally 63 composed of a head 64 having an integral handle 65 projecting therefrom. As best seen in Figure 13, the head 64 is provided with a recess 66 which extends therethrough and which has a restricted opening 67 opening laterally outwardly of the head at a side thereof remote to the handle 65 and forming complementary jaw portions 68. The head 64 is formed of a material possessing sufficient resiliency so that the jaw portions 68 thereof are capable of yielding slightly away from one another. The toy 62 also includes a peg or rod 69, corresponding to the peg 23 and which is provided with longitudinal slots 70 and caps 71 at the ends thereof. The peg 69 extends reciprocally through the bore 66 and is yieldably gripped thereby due to the resiliency of the peg afforded by the slots 70 and also by the resiliency of the head portion or jaws 68. The toy 62 is utilized in the same manner and for the same purpose as the toys 15, 28, 42 and 53.

Various other modifications and changes are contemplated and may obviously be resorted to, without departing from the spirit or scope of the invention as hereinafter defined by the appended claims.

I claim as my invention:

1. A striking or hammering toy comprising a body having a bore extending therethrough, and an elongated peg extending reciprocally through said bore and sized to be frictionally engaged by the wall of the bore, said peg being of a length greater than the length of said bore and extending to beyond each end of the bore to enable the body to move longitudinally of the peg toward either end thereof when said end is struck against a surface, said body being substantially mallet-shaped and including a head and an elongated handle projecting laterally from said head, said bore extending longitudinally through the head and being disposed with its longitudinal axis perpendicular to the longitudinal axis of the elongated handle.

2. A striking or hammering toy comprising a body having a bore extending therethrough, and an elongated peg extending reciprocally through

said bore and sized to be frictionally engaged by the wall of the bore, said peg being of a length greater than the length of said bore and extending to beyond each end of the bore to enable the body to move longitudinally of the peg toward either end thereof when said end is struck against a surface, said body being substantially mallet-shaped and including a head and an elongated handle projecting laterally from said head, said bore extending longitudinally through the head, said head being provided with a transversely extending recessed portion to receive one end of the handle, said end of the handle having a bore therein for registration with the bore of the head and through which the peg extends.

3. A striking or hammering toy comprising a body having a bore extending therethrough, and an elongated peg extending reciprocally through said bore and sized to be frictionally engaged by the wall of the bore, said peg being of a length greater than the length of said bore and extending to beyond each end of the bore to enable the body to move longitudinally of the peg toward either end thereof when said end is struck against a surface, said body including an elongated handle and a head connected to one end of the handle, said head being provided with an opening forming said bore for reciprocally receiving the peg, said handle projecting from the head at a right angle to the axis of the bore.

4. A striking or hammering toy comprising a body having a bore extending therethrough, and an elongated peg extending reciprocally through said bore and sized to be frictionally engaged by the wall of the bore, said peg being of a length greater than the length of said bore and extending to beyond each end of the bore to enable the body to move longitudinally of the peg toward either end thereof when said end is struck against a surface, said body including a head in which the bore is formed and a handle, said head having a recess disposed at a right angle to the axis of the bore and intersecting the same, said handle having an end detachably disposed in said recess and provided with a bore for registration with the bore of the head and through which the peg extends.
